[57] ABSTRACT

A learning machine in which threshold values corresponding to the desired output conditions and having a dead zone therebetween are used during the learning process for the discrimination of the output from a memory storing a plurality of standard pattern information, and this discriminating faculty is utilized for the discrimination of input pattern information with respect to a single threshold value having no dead zone. Thus, the precision of discrimination can be remarkably improved due to the fact that the threshold values having a dead zone are used during the learning process, and the learning can be digitally and automatically carried out.

FIG. 8

LEARNING MACHINE

This invention relates to learning machines and more particularly to a learning machine of the kind having such a learning faculty that a set of given input conditions and a set of output conditions given for the input conditions are simultaneously stored in a memory so as to derive any desired output condition therefrom.

Learning machines of this kind are generally provided with an adaptive logic circuit which has such a learning faculty that an output satisfying the desired condition can be obtained for each input condition so that a correct output response can be provided for each input condition after learning. In addition to the above, retraining can be done as required so as to deliver a new output response for a new input condition.

Referring to FIG. 1 showing the basic structure of a learning machine of this kind, it comprises a plurality of weight elements A, B, C, . . . having respective weight factors W_1 , W_2 , W_3 , . . . which may, for example, be a voltage, a summing circuit D, a decision circuit E, an output terminal F, a terminal G to which a desired output is applied, and a learning control circuit H. A plurality of input signals X_1 , X_2 , X_3 , . . . are applied to the respective weight elements A, B, C, . . . and a threshold value W_0 is applied to the decision circuit E. The inputs X_1 , X_2 , X_3 , . . . may be one of a set of "1" and "0" or one of a set of "+1" and "-1." The inputs X_1 , X_2 , X_3 , . . . are multiplied by the weights W_1 , W_2 , W_3 , . . . of the respective weight elements A, B, C, . . . and the products are summed up in the summing circuit D. The sum is compared with the threshold value W_0 in the decision circuit E, and the output delivered from the decision circuit E is "+1" and "0" respectively when the sum is larger and smaller than the threshold value W_0 in the embodiment of the present invention described hereinbelow.

In the learning machine having a structure as described above, when the actual output for a certain input condition is "+1" and the desired output is "0," the learning control circuit H adjusts the weight factors until they are decreased to give the actual output "0." The above procedure is repeated for all the input patterns each consisting of a set of numerals so that all the input patterns can be classified into two categories consisting of a class 1 and a class 2.

However, such a system has been defective in that man must participate in the discriminating faculty in the course of learning and thus an extremely extended period of time is required for the learning. Further, due to the fact that the decision circuit E acts as a one-out-of-two decision element during the learning process, there is a problem that correct decision cannot be expected during the stage of discrimination when an input pattern differs slightly from a standard pattern.

The present invention contemplates the provision of a learning machine which is free from the above problem by virtue of the fact that it is provided with a memory for storing a plurality of standard patterns and a decision circuit acting as a one-out-of-three decision element during the learning process so as to cooperate with threshold values having a dead zone therebetween.

It is an object of the present invention to provide a learning machine which is provided with a memory and an automatic learning circuit so that a plurality of standard pattern information written previously in the memory can be automatically derived so as to effect discrimination within a short period of time.

Another object of the present invention is to provide a learning machine in which the classification of standard patterns in a decision circuit during the learning process is carried out on the basis of threshold values having a dead zone therebetween and the discrimination is effected on the basis on only one threshold value as heretofore so as to enhance the precision of discrimination.

The above and other objects, features and advantages of the present invention will be apparent from the following detailed description taken in conjunction with the accompanying drawings, in which:

FIG. 1 is a block diagram showing the basic structure of a learning machine;

FIG. 2 is a block diagram showing the structure of an improved learning machine according to the present invention;

FIGS. 3 through 6 and 8 are circuit diagrams showing the detail of parts of the learning machine shown in FIG. 2; and

FIGS. 7a and 7b are charts showing the operation of parts of the structure shown in FIG. 6.

Referring to FIG. 2, a plurality of inputs are applied to respective input terminals 1, 2 and 3 and are held in respective circuits 4, 5 and 6 for any desired period of time. The circuits

10 4, 5 and 6 may be bistable multivibrators. A plurality of weight factor selective circuits 7, 8 and 9 include weight elements for multiplying the outputs from the bistable multivibrators 4, 5 and 6 by respective weight factors W_7 , W_8 and W_9 . Although there are actually n input terminals, n bistable multivibrators and n weight factor selective circuits, only three of them are shown herein for the sake of simplicity. The input signals applied to the input terminals 1, 2 and 3 are either "1" or "0," and these signals are multiplied by the respective weight factors W_7 , W_8 and W_9 so that the products appear at the output sides of the respective weight factor selective circuits 7, 8 and 9.

A memory 10 stores successively the outputs from the bistable multivibrators 4, 5 and 6, and at the same time, stores successively expected outputs for standard patterns applied from a terminal 11. A trigger pulse generator 12 controls the writing and reading of input patterns into and out of the memory 10 during the learning process, depending on a signal applied thereto from a manual signal input terminal 13 or an output 20 signal delivered from a learning pulse generator 14 having a function which will be described later.

A summing circuit 15 sums up the weighted values delivered from the weight factor selective circuits 7, 8 and 9.

A decision circuit 16 compares the output from the summing 35 circuit 15 with a threshold value W_0 . Thus, an output "+1" appears at an output terminal 17 when the sum is larger than the threshold value W_0 and an output "0" appears at the output terminal 17 when the sum is smaller than the threshold value W_0 . A threshold value selection circuit 18 supplies to the decision circuit 16 the threshold value W_0 corresponding to a desired output which may be "+1" or "0" appearing at an output terminal 101 of the memory 10 during learning, while a threshold value W_0' applied to the selection circuit 18 from an input terminal thereof is directly supplied to the decision circuit 16 during discrimination.

The learning pulse generator 14 compares the actual output appearing at the terminal 17 during the learning process with the desired output appearing at the output terminal 101 of the memory 10 and sends a series of learning pulses to the weight factor selective circuits 7, 8 and 9 to vary their weight factors only when the actual output does not coincide with the desired output. A weight factor decrement control signal, a weight factor increment control signal and a learning pulse signal appear at respective output terminals 141, 142 and 143 (FIG. 5) 55 of the learning pulse generator 14.

The practical structure of the memory 10, trigger pulse generator 12, learning pulse generator 14, summing circuit 15, decision circuit 16, threshold value selection circuit 18, and 60 weight factor selective circuits 7, 8 and 9 which are the principal components of the learning machine according to the present invention will be described in detail.

The practical structure of the memory 10 is shown in FIG. 3. The function of the memory 10 is to store standard patterns and output signals desired for the patterns as described above. In storing the standard patterns and the desired outputs therefor, a switch S_1 is thrown to the side of the terminals a and b to apply a voltage of $-E$ volts to the gates of gating transistors G_1 , G_2 , G_3 and G_4 so as to urge these transistors to 70 conduct. The desired output supplied from the terminal 11 is written in a memory means such as a shift register SR_1 through the transistor G_1 , while the components constituting the standard pattern supplied from the bistable multivibrators 4, 5 and 6 are written in memory means such as shift registers SR_2 , SR_3 and SR_4 through the transistors G_2 , G_3 and G_4 .

In reading out the contents written in the shift registers SR₁, SR₂, SR₃ and SR₄, the switch S₁ is thrown to the side of the contacts c and d so that the shift registers SR₁, SR₂, SR₃ and SR₄ are connected in a ring with respective transistors G₅, G₆, G₇ and G₈. On the other hand, the gates of the transistors G₁, G₂, G₃ and G₄ are grounded and these transistors are cut off. The contents stored in the shift registers SR₁, SR₂, SR₃ and SR₄ are read out by the pulse supplied from the trigger pulse generator 12 and are rewritten in the shift registers SR₁, SR₂, SR₃ and SR₄ through the respective transistors G₅, G₆, G₇ and G₈. The outputs appearing at terminals 101, 102, 103 and 104 are applied to the learning pulse generator 14 and the threshold value selection circuit 18, and to the bistable multivibrators 4, 5 and 6, respectively.

The practical structure of the trigger pulse generator 12 is shown in FIG. 4. A manual signal is applied from the terminal 13 to a pulse generator PG₁ in the case of the writing of the standard pattern in the memory 10. The pulse generator PG₁ is thereby energized to generate clock pulses. During the learning process, the output from the learning pulse generator 14 is applied to the pulse generator PG₁ which therefore generates clock pulses. A bistable multivibrator BS₁ is provided so as to stop the operation of the learning pulse generator 14 and the bistable multivibrator BS₁ is restored to the original state by a signal applied thereto through a delay means DE₁ and a monostable multivibrator MS₁.

FIG. 5 shows the practical structure of the learning pulse generator 14 which functions to supply the learning pulses to the weight factor selective circuits 7, 8 and 9 when the standard pattern information stored in the memory 10 is successively read out from the memory 10 for the necessity of learning.

The relation among a desired output for a standard pattern, an actual output or output from the decision circuit 16, necessity of learning, and an increase or decrease in weights due to the requirement for learning is tabulated in Table 1.

Table 1

Case	I	II	III	IV
Desired output	+1	0	+1	0
Actual output	+1	+1	0	0
Learning	not required	required	required	not required
Increase or decrease in weights	—	decrease	increase	—

In the table, "+1" represents a high level at +5 volts and "0" represents a low level at 0 volts.

Suppose, for example, that the conditions of the case I or IV are satisfied for a standard pattern, then it is apparent that any change in the weight factors of the weight elements in the weight factor selective circuits 7, 8 and 9 is unnecessary. More precisely, the inputs applied to an AND-gate A₁ include the actual output and the desired output which is passed through an inverter I₁, while the inputs applied to a NAND-gate NA₁ include the desired output and the actual output which is passed through an inverter I₂. Thus, one of the three input signals applied to the AND-gate A₁ and NAND-gate NA₁ is in the low level and the two input signals applied to a NAND-gate NA₂ remain in their high level with the result that a bistable multivibrator BS₃ is not actuated and no learning pulse is generated. In the case II, the desired output is in the low level and the actual output is in the high level. Therefore, all the input signals applied to the AND-gate A₁ are in the high level, and a bistable multivibrator BS₂, a monostable multivibrator

MS₂ and the NAND-gate NA₂ are operated. When the monostable multivibrator MS₂ generates one pulse, the bistable multivibrator BS₃ generates a plurality of pulses, for example, five pulses the number of which is equal to the number of variable stages of the weight factors, and thus five learning pulses are supplied to the weight factor selective circuits 7, 8 and 9. In this case, a negative voltage pulse of pulse width including the first pulse delivered from the bistable multivibrator BS₃ appears at the decrement control signal output terminal 141. In the case III, the desired output is in the high level and the actual output is in the low level. Therefore, all the input signals applied to the NAND-gate NA₁ are in the high level so that the bistable multivibrator BS₃ and the monostable multivibrator MS₂ are operated to supply one learning pulse to the weight factor selective circuits 7, 8 and 9 from the terminal 143. In the meantime, a negative voltage at -10 volts appears at the increment control signal output terminal 142. B₁ and B₂ are buffer circuits. When the actual output coincides with the desired output in the course of the above operation, a signal is delivered from an AND-gate A₂ to drive the trigger pulse generator 12 so that the same operation is repeated for the next standard pattern. When no coincidence is reached between the actual output and the desired output, the operation described above is repeated.

FIG. 6 shows the practical structure of the summing circuit 15, the decision circuit 16 and the threshold value selection circuit 18. The summing circuit 15 includes an operational amplifier OP₁ and sums up the outputs from the weight factor selective circuits 7, 8 and 9. The threshold value selection circuit 18 delivers an output W_0 which is supplied to the decision circuit 16 as the threshold value. An operational amplifier OP₂ in the decision circuit 16 delivers "+1" and "0" respectively when the output from the summing circuit 15 is larger and smaller than the threshold value W_0 .

During learning, the threshold value selection circuit 18 supplies to the decision circuit 16 threshold values having a dead zone therebetween, while during discrimination, it supplies a threshold value having no dead zone. The threshold value selection circuit 18 has thus a function of selecting its output depending on the desired output. When, for example, a desired output "+1" appearing at the output terminal 101 of the memory 10 is applied to the threshold value selection circuit 18, it delivers an output $+\omega$, while when a desired output "0" is applied thereto, it delivers an output $-\omega$. These outputs $+\omega$ and $-\omega$ provide the threshold values employed in the decision circuit 16.

Therefore, the necessity of learning is concerned with the magnitude of the output

50

$$\sum_{i=1}^n X_i W_i$$

from the summing circuit 15 relative to the magnitude of the threshold value $+\omega$ or $-\omega$ corresponding to the desired output "+1" or "0." In the case I in Table 1, there is no necessity for learning and any increase or decrease in the weight factors of the weight factor selective circuits 7, 8 and 9 is unnecessary since the output from the decision circuit 16 coincides with the desired output. This applies also to the case IV. In the case II, the output from the decision circuit 16 is "+1," whereas the desired output is "0." In this case, the following relation exists between the output from the summing circuit 15 and the threshold value $-\omega$:

$$\sum_{i=1}^n X_i W_i > -\omega$$

70 However, actually the following relation must hold between the output from the summing circuit 15 and the threshold value $-\omega$:

$$\sum_{i=1}^n X_i W_i < -\omega$$

75

In order to satisfy the above condition, the weight factors W_7 , W_8 and W_9 of the respective weight elements in the weight factor selective circuits 7, 8 and 9 must be decreased to reduce the output from the summing circuit 15. The situation is opposite in the case III. That is, the weight factors W_7 , W_8 and W_9 must be increased, and the learning is completed when the output from the summing circuit 15 exceeds the threshold value $+\omega$. By the above manner of learning process, the case II is shifted to the case IV, while the case III is shifted to the case I.

Since the desired output is applied to the threshold value selection circuit 18 during learning to determine the corresponding threshold value in the manner described above, a dead zone exists between the threshold values $+\omega$ and $-\omega$ corresponding to the desired outputs "1" and "0" as shown in FIG. 7a. Thus, the decision circuit 16 has a function of a one-out-of-three decision element. In FIGS. 7a and 7b, the horizontal axis represents the output

$$\sum_{i=1}^n X_i W_i$$

from the summing circuit 15, and the vertical axis represents the output from the decision circuit 16.

Referring to FIG. 6 again, a switch S_3 in the threshold value selection circuit 18 is thrown to the side of the terminal a in the case of the learning and to the side of the terminal b in the case of the discrimination. When the switch S_3 is thrown to the side of the terminal a to connect an operation amplifier OP_3 to the decision circuit 16, the threshold value W_0 supplied from the threshold value selection circuit 18 to the decision circuit 16 corresponds to the desired output "1" or "0" stored in the memory 10, while when the switch S_3 is thrown to the side of the terminal b , the threshold value W_0 supplied from the threshold value selection circuit 18 to the decision circuit 16 is proportional to the threshold value W'_0 . In the case of the discrimination, the decision circuit 16 acts as a conventional one-out-of-two decision element because there is only one threshold value as seen in FIG. 7b.

FIG. 8 shows the practical structure of the weight factor selective circuit 7 including the weight element. The remaining weight factor selective circuit 8 and 9 have the same structure as the selective circuit 7. The weight factor of the weight element is variable over five levels which are +2 volts, +1 volts, 0 volts, -1 volts and -2 volts.

Five bistable multivibrators BS_4 , BS_5 , BS_6 , BS_7 and BS_8 have the function of selecting the weight factor and the outputs from the respective bistable multivibrators control the conduction and cutoff of five gating transistors G_9 , G_{10} , G_{11} , G_{12} and G_{13} . More precisely, when anyone of the bistable multivibrators BS_4 , BS_5 , BS_6 , BS_7 and BS_8 delivers an output "1" at a level of -10 volts (herein, the negative logic is applied), the voltage at the drain electrode of the transistor connected to the output of the specific bistable multivibrator appears at its source electrode. Suppose that the input signal is applied from the bistable multivibrator 4, which sets the potential of the gate electrode of a transistor G_{17} at a level of 0 volts, this transistor G_{17} is cut off and the voltage appearing at the source electrode of the specific transistor is supplied to the summing circuit 15 as the weight. Since two or more outputs of the bistable multivibrators BS_4 , BS_5 , BS_6 , BS_7 and BS_8 cannot simultaneously take the value "1," only one of the five voltages representing the respective weights should appear as the weight. Gating transistors G_{14} , G_{15} and G_{16} are cut off when their gate voltage is 0 volts. Only when all of these three transistors G_{14} , G_{15} and G_{16} are in their cutoff state, the learning pulses are applied from the terminal 143 of the learning pulse generator 14 to the bistable multivibrators BS_4 , BS_5 , BS_6 , BS_7 and BS_8 via a point A to shift the same. As soon as the first one of the five learning pulses arrives from the terminal 143 of

the learning pulse generator 14, a decrement control signal of negative voltage is supplied from the terminal 141 of the learning pulse generator 14. Thus, a negative potential appears at the gate of the transistor G_{18} provided that one of the bistable multivibrators BS_4 , BS_5 , BS_6 , BS_7 and BS_8 is delivering "1." As a result, the transistor G_{18} conducts to short circuit the point A to ground and the first one of the five learning pulses cannot reach the bistable multivibrators BS_4 , BS_5 , BS_6 , BS_7 and BS_8 . A decrement control signal of 0 volts is applied as soon as the second one of the five learning pulses appears, and the transistor G_{18} is thereby cut off so that the remaining four learning pulses are applied to the bistable multivibrators BS_4 , BS_5 , BS_6 , BS_7 and BS_8 . Consequently, the position of the output "1" from the bistable multivibrators BS_4 , BS_5 , BS_6 , BS_7 and BS_8 is shifted to the lower place, and this is followed by stepdown of the weight level by one step. When the bistable multivibrator BS_4 is delivering "1," the transistor G_{18} is cut off due to the fact that 0 volts is applied to the gate thereof, and all of the five learning pulses pass through the point A to shift the position of "1" until it returns to the bistable multivibrator BS_4 again so that no shift can substantially occur. Similarly, an increment control signal of negative voltage appears as soon as the learning pulses are supplied from the terminal 143 of the learning pulse generator 14, and since the transistor G_{18} is cut off unless the bistable multivibrator BS_8 is delivering "1," the position of the output "1" is shifted to the higher place in response to the learning pulses.

The learning machine having a structure as described above operates in a manner as described below. Input pattern information supplied from the terminals 1, 2 and 3 is stored in the bistable multivibrators 4, 5 and 6, and at the same time, written in the memory 10. The desired outputs for the input patterns are also written in the memory 10 from the terminal 11. This operation is repeated for standard input patterns following the above-described input patterns so that the information of all the standard patterns is stored in the memory 10. When it is desired to make automatic learning on the basis of this information so as to obtain the desired output condition, the switch S_1 in FIG. 3 is switched over to urge the transistors G_5 , G_6 , G_7 and G_8 to conduct and to cut off the transistors G_1 , G_2 , G_3 and G_4 . Each time the clock pulse is supplied from the trigger pulse generator 12 to the memory 10, the stored information is supplied to the learning pulse generator 14 and the bistable multivibrators 4, 5 and 6 from the respective output terminals 101, 102, 103 and 104 of the memory 10. The information supplied to the bistable multivibrators 4, 5 and 6 is weighted by the weight factor selective circuits 7, 8 and 9, and is passed through the summing circuit 15 to be applied to the decision circuit 16 wherein the sum is compared with the threshold value W_0 and the result appears at the output terminal 17 as an output "1" or "0." In this process, the switch S_3 in the threshold value selection circuit 18 is connected to the output terminal 101 of the memory 10 so that the threshold value W_0 corresponds to the value "1" or "0." Thus, the decision circuit 16 has a function similar to the function of a one-out-of-three decision element for the threshold values having a dead zone therebetween and the output therefrom is classified under a severe condition compared with the classification by a one-out-of-two decision element. The actual output and the desired output are compared with each other in the learning pulse generator 14. When the actual output does not coincide with the desired output, the learning pulses and control signals are supplied to the weight factor selective circuits 7, 8 and 9 so as to bring coincidence therebetween, whereby the learning can proceed in the manner of error correction. When the learning proves that the actual output coincides with the desired output, the trigger pulse generator 12 is actuated to draw out the next information from the memory 10 by the clock pulse and a similar operation is carried out. As the above operation is repeated, the actual output becomes to always coincide with the desired output thereby completing the learning. When discriminating any input pattern after the learning is completed, the switch S_3

in the threshold value selection circuit 18 is switched over to the side giving the threshold value W_s' so that the decision circuit 16 acts as a conventional one-out-of-two decision element.

What is claimed is:

1. A learning machine comprising a memory for storing a plurality of standard pattern information, a plurality of weight elements connected to respective weight selective circuits for applying a variable weight factor, selecting means for selecting the output from said memory and input pattern information to be discriminated, a threshold value selection circuit, a decision circuit for generating an output corresponding to the relative magnitude of the sum of outputs from said weight elements and an output supplied from said threshold value selection circuit, and a learning pulse generator for supplying learning pulses to said weight selective circuits thereby varying the weight factors of said weight elements when the output from said decision circuit does not coincide with a desired output and driving said memory for deriving the next standard pattern information when the output from said decision circuit coincides with the desired output, whereby the standard pattern information can be successively learned for the discrimination of input pattern information.

2. A learning machine as claimed in claim 1, in which said memory comprises a plurality of shift registers, first gate means connected across the input and output terminals of said shift registers, second gate means interposed between signal input terminals and the input terminals of said shift registers, and common selectively conducting means for causing one of the groups of said first and second gate means to conduct while cutting off the other group, so that said first gate means are cut off and said second gate means are urged to conduct by said selectively conducting means so as to successively write the standard pattern information supplied from said signal input terminals in said shift registers, and at the completion of the writing, said second gate means are cut off and said first gate means are urged to conduct by said selectively conducting means so as to successively supply the standard pattern information stored in said shift registers to said weight elements, and at the same time, to circulate same through said first gate means.

3. A learning machine as claimed in claim 1, in which each said weight selective circuit comprises a plurality of bistable multivibrators connected in cascade, first gate means for gating the output from said learning pulse generator and supplying a trigger pulse to said bistable multivibrators and a plurality of second gate means applied with different voltages

representative of weight factors, so that one of said second gate means is selected by the output from said bistable multivibrators connected in cascade.

4. A learning machine as claimed in claim 1, in which each said weight element comprises gate means which controls the passage of the voltage representative of the weight factor supplied from said weight selective circuit in response to the standard pattern information supplied from said memory or the externally supplied input pattern information to be discriminated.

5. A learning machine as claimed in claim 1, in which said learning pulse generator comprises two inverse coincidence circuits to which the output from said decision circuit and the desired output are applied as inputs, first pulse-generating means connected to one of said inverse coincidence circuits, weight factor decrement control signal generating means connected to said first pulse-generating means for controlling the decrement of the weight factor, weight factor increment control signal generating means receiving the output from the other said inverse coincidence circuit for controlling the increment of the weight factor, second pulse-generating means receiving the output from the other said inverse coincidence circuit and the output from said first pulse-generating means for responding to the logical sum of the inputs thereto for generating at least one learning pulse, and third pulse-generating means for reading out another standard pattern information stored in said memory upon detection of the coincidence between the two inputs applied to said inverse coincidence circuits.

15 6. A learning machine as claimed in claim 1, in which said threshold value selection circuit comprises selecting means for selecting one of a set of a desired output and a threshold value, and the desired output is selected during learning so that it is supplied as the threshold value.

30 7. A learning machine as claimed in claim 1, in which said threshold value selection circuit comprises means for selecting one of means generating a threshold value representative of a desired output and means generating a single threshold value and supplying the output from the selected means to said decision circuit.

35 8. A learning machine as claimed in claim 1, further comprising a trigger pulse generator having pulse-generating means for generating a pulse in response to an output pulse supplied from said learning pulse generator, and means for stopping the operation of said learning pulse generator for a predetermined period of time in response to the output from said pulse-generating means.
